UNITED STATES PATENT OFFICE.

CLARENCE HARRER, OF PORT WASHINGTON, WISCONSIN.

AUTOMATIC BOTTLE CLOSURE.

Application filed September 14, 1920. Serial No. 410,223.

To all whom it may concern:

Be it known that I, CLARENCE HARRER, a citizen of the United States, and resident of Port Washington, in the county of Ozaukee and State of Wisconsin, have invented certain new and useful Improvements in Automatic Bottle Closures; and I do hereby declare that the following is a full, clear, and exact description thereof.

10 My invention relates to new and useful improvements in receptacle closures, especially those which are adapted to be automatic in their operation.

It is the principal object of this invention 15 to provide a closure for such articles as syrup pitchers and liquid containers generally which will readily swing to open position when the receptacle is tilted to empty the contents, and automatically return to closed 20 position when the receptacle is upright.

An additional object of the invention is to provide a closure of this character in which springs and like operating means have been eliminated.

25 A further object of the invention is to provide means for closing receptacle covers which is so arranged that the force of the undischarged fluid in returning to its level in the receptacle will operate to aid in shutting the closure.

With these general objects in view, the invention resides in the novel features of construction, combination and arrangement of parts which will be hereinafter more particularly described and claimed.

35 In the accompanying drawing,

Figure 1 represents a vertical sectional view taken substantially on the plane of the line 1—1 of Figure 2, and showing the preferred manner of constructing the invention, and

40 Figure 2 is a plane view of the structure as shown in Figure 1.

Referring more particularly to the drawing, it will be noted that the reference character 1 pertains to a receptacle or container of any desired size or shape, having a spout attaching member 2 seated in its neck. This attaching member consists of a receptacle 45 engaging nozzle 3 and an internal threaded spout receiving cup 4. A spout 5 is secured to the attaching member 2 by a reduced and threaded end 6, the spout engaging portion 50 of said member 2 being in contact with a flange 7 as is most clearly shown in Figure 1.

This spout 5 has its upper open end provided with a cover 8 which is hinged at one side as at 9. Depending from the cover 8 adjacent the hinge thereof and disposed within the spout 5 is a hanger rod 10, the same having a ball or any suitably shaped weight 11 on its lower free end. When the cover 8 is closed the hanger rod is disposed vertically and adjacent the hinged side of the spout wall.

When, however, the receptacle 1 and the spout 5 are tilted to discharge the contents, the weight 11 will tend to drop toward the opposite wall of the spout from that which it is normally adjacent, thus swinging the cover 8 on its hinge 9 to an open position. When a sufficient quantity of the fluid contents has been discharged, the container is returned to upright position and the cover 75 is automatically closed by the swinging action of the hanger rod 10 and its weight 11 as they return to their position of rest. Obviously any liquid which tends to flow back into the container from the open end of the 80 spout will strike against the weight 11 and thus urge it into its normal inactive position. This feature is particularly beneficial in aiding the weight to return the cover to closed position when there is any tendency 85 of the latter to stick.

It will also be noted that the spout may be detached from the cup 4, owing to the threaded connection 6. This is very convenient when refilling the bottle since the cup 4 90 will act as a funnel. It is not desirable to remove the neck portion 3 or the attaching portion 2 since the latter includes the downwardly extending cork portion which forms a lining for the neck of the bottle and is 95 comparatively thin and easily broken.

From the foregoing description taken in connection with the accompanying drawing, it will be appreciated that I have invented a very simply constructed automatic 100 closure which can be applied to various types of receptacles and containers, and one which can be inexpensively manufactured in a great variety of shapes and styles. In other words, various changes may be made 105 to form portions of the different parts of the invention without departing from the principles thereof or sacrificing any of its advantages.

I claim:

110 A bottle closure comprising a hollow neck engaging portion having its upper end

flared to form a comparatively wide mouth through which the bottle may be filled, a spout detachably connected to said flared end at the topmost portion of said flared end, an annular rib on said spout adapted to rest on the edge of said flared end, a cover for said spout, and gravity actuated means for automatically opening and closing said cover, said spout being

increased in cross sectional area adjacent to 10 said flared end to provide space for said gravity actuated means.

In testimony that I claim the foregoing I have hereunto set my hand at Port Washington, in the county of Ozaukee and State of 15 Wisconsin.

CLARENCE HARRER.
